ALBERT C. MINER, OF PHILADELPHIA, PENNSYLVANIA, ASSIGNOR TO HIMSELF AND JAMES GUILD, OF WASHINGTON, DISTRICT OF COLUMBIA.

Letters Patent No. 78,990, dated June 16, 1868.

IMPROVEMENT IN RAILROAD-CAR HEATERS.

The Schedule referred to in these Letters Patent and making part of the same.

TO ALL WHOM IT MAY CONCERN:

Be it known that I, ALBERT C. MINER, of city and county of Philadelphia, and State of Pennsylvania, have invented a new and useful Improvement in Railroad-Car Heater and Fire-Extinguisher; and I do hereby declare the following to be a clear and exact description of the nature thereof, sufficient to enable others skilled in the art to which my invention appertains to fully understand and use the same, reference being had to the accompanying drawings, making part of this specification, in which—

Figure 1 is a longitudinal vertical section of a passenger-car.

Figure 2 is a transverse vertical section thereof.

Figure 3 is a plan of the floor thereof.

Similar letters of reference indicate corresponding parts in the several figures.

The nature of my invention consists in the application of steam to railroad-cars, for the purpose of warming passenger-cars, which result is accomplished in a manner as will be hereinafter more fully described.

In the drawings, A represents a baggage or mail-car, and A' the floor thereof, and underneath which is placed the steam-service pipe B, having branch-pieces B¹, into which the tube B and the valve branch-pipes are screwed.

B² represents the branch-pipes which lead into the car. Suitable stop-cocks or valves C are employed to regulate the supply of steam in the car, and stop-cocks or valves C' regulate the supply of steam to the service-pipe or train.

The series of steam-pipes will be connected together by flexible pipes D', whose ends are held by couplings D.

The parts thus described, with the exception of valves C, are also applied to the passenger-car E, represented in fig. 3. On the floor of this car, I place longitudinally, a steam-box, E', which should be constructed of cast iron, or other suitable metal, and extend the entire length of the car.

The pipes B² open into the box, and admit steam therein. The top of the box should be a little below the level of the floor of the car, and on this top I place a metal floor, e³, whose upper face is corrugated or fluted transversely, and should be flush with the floor of the car. This corrugated floor serves to protect the feet of passengers, when walking along the aisles of the car.

Suitable ventilating-holes should be made in the box to permit the heat from the sides and bottom thereof to pass up into the car, and thereby provide against the loss of heat.

Now, in order to heat the cars, the valves C' are opened, and the steam will enter the pipes B, and circulate in the box E', while the heat will radiate from said box and diffuse itself throughout the car.

A small steam-box can be placed at one end of the mail and baggage-cars, in order to warm said cars, but I may employ boxes of the entire length of those cars.

Since there will be no stoves in the passenger-cars, the greatest danger from fire to the train will be from the furnace of the locomotive. The baggage and mail-cars are naturally the first exposed. Fire soon is communicated to them, in view of the combustible nature of the mails and trunks.

In order to extinguish any fire that may thus occur, I design to inject the steam directly into said cars. For this purpose the pipes B² open into the cars, and are provided with light cap-valves b. These valves lie on the pipes and close them when the steam is not admitted, and are flush with the floor.

In case of fire in the baggage or mail-car, the stop-cocks C C' are turned on, and the steam immediately blows open the valve b, fills the car, and thus subdues or extinguishes the fire.

A safety-valve will be secured to the main pipe, under the tender, and a suitable gauge will be within sight of the engineer, so that the pressure of steam for the cars will be always known, and may be regulated accordingly.

Having thus described my invention, what I claim as new, and desire to secure by Letters Patent, is—

The steam-box E', having its upper face corrugated, and forming the floor of the car E, in combination with the pipes B B¹ B², and valves C C', when constructed and operating as herein represented and described.

In testimony whereof, I have signed my name to this specification in the presence of two subscribing witnesses.

ALBERT C. MINER.
